(57) **CLAIM**

The ornamental design for a candy, as shown and described.

DESCRIPTION

The ornamental design of this invention is a candy stick with an attached circular body having a front face and a back face, a circumferentially extending rim protruding from the front face, a curved elongated bulge, and a pair of spaced apart circular protrusions. The bulge and the protrusions protrude outwardly from the front face and are positioned and shaped to represent the mouth and eyes of a stylized face.

FIG. 1 is a perspective view of a candy in accordance with the invention;

FIG. 2 is a front plan view of the candy of FIG. 1;

FIG. 3 is a side elevational view of the candy of FIG. 1;

FIG. 4 is a rear plan view of the candy of FIG. 1;

FIG. 5 is a perspective view of a second embodiment of a candy as shown in FIG. 1, featuring a circumferentially extending rim which protrudes from the front and back faces;

FIG. 6 is a front plan view of the candy of FIG. 5;

FIG. 7 is a side elevational view of the candy of FIG. 5; and,

FIG. 8 is a rear plan view of the candy of FIG. 5.
